UNITED STATES PATENT OFFICE.

ELMER A. WATTS, OF SPRINGFIELD, OHIO, ASSIGNOR TO THE MILLER IMPROVED GAS ENGINE COMPANY, OF SPRINGFIELD, OHIO, A CORPORATION OF OHIO.

CYLINDER-HEAD CONSTRUCTION FOR INTERNAL-COMBUSTION ENGINES.

Application filed October 29, 1924. Serial No. 746,481.

My invention relates to internal combustion engines and in particular to certain valve casing and cylinder head construction.

5 It is the object of my invention to provide a combined cylinder head and valve casing construction which shall provide suitable water cooled valves and a cylinder head detachable from the cylinder and 10 adapted to accommodate itself to the pressures, heats and expansions common to such construction without injury to itself or to the mechanism upon which it is mounted.

It is essential in a construction of this 15 sort to provide adequate cooling facilities for the cylinder head and adequate means for permitting of the expansion of the head under the varying temperatures and pressures to which it is subjected, and independent expansion of the valve casings.

It is my object, therefore, to provide means to prevent warping, to provide means for the ready opening of the head for its inspection and cleaning, and means for providing cool valves so that there will be the minimum of warping of the valves and consequent leakage and defective operation of the internal combustion engine.

It is a further object to provide a valve 20 casing which will provide a ready means of attachment and support for large area intake and exhaust manifolds.

By my construction I have been able to solve the problem of carrying fluids in large 25 quantities around the valves both internally and externally. I have further been able to provide other large valves for the ready intake of the fuel and its rapid evacuation from the exhaust.

40 It is a further object of my invention to provide a convex cylinder head to insure the expansion of the head outwardly, such expansion outwardly serving to maintain the same relative position of the several associated parts.

Referring to the drawings:

Figure 1 is a section through the valve casing construction on a vertical plane passing through the valves transversely of the 50 main axis of the engine, showing the water cooling process for the exterior of the valve casings proper and the water cooling of the interior of the valves themselves;

Figure 2 is an end elevation from the outside of the end of the engine having the valve casting with the end plate of the casting removed for the inspection of the interior of the water cooling passageways;

Figure 3 is a side elevation of the casting;

Figure 4 is a top plan view of the casting;

Figure 5 is a bottom plan view of the casting;

Figure 6 is a section taken on a vertical plane through the housing perpendicular to and transversely of the major axis of the internal combustion engine on the line 6—6 of Figure 7;

Figure 7 is a section on the line 7—7 of Figure 6 looking in the direction of the arrows;

Figure 8 is a section on the line 8—8 of Figure 6;

Figure 9 is a section on the line 9—9 of Figure 6;

Figure 10 is a section on the line 10—10 of Figure 6;

Figure 11 is a section on the line 11—11 of Figure 8; and

Figure 12 is a section on the line 12—12 of Figure 6.

Fig. 13 is a detail section showing the guide and adjustment for the valve stem.

It will be generally understood that this combined cylinder head and valve casing construction consists of a single casting having an intake passage way connected to the source of fuel supply, which passage way is connected with the interior of the cylinder through the inlet valve. The casting is provided with a similar inside part through the head of the cylinder into the valve casing which part connects with the exhaust manifold attached to the casing. We thus have a unitary structure consisting of a water cooled casing for the valves and the cylinder head, which casing can be applied as a unit to the end of the cylinder and joined up with the water cooled passageways of the cylinder. Means are also provided for cooling the interior of the exhaust valve and its guides to reduce warping and insure perfect seating in such valve.

With this general understanding, the following detail description of the mechanism

will be more readily understood. The casting consists of an integral top having an outer wall and spaced from this outer wall a pair of tubular members which form the valve casings proper.

The inside of the casting consists of a finished plate or ring 1 through which are pierced the apertures 2 for the reception of the bolts which attach the casting to the head of the cylinder. This ring merges into the outside wall 3 of the casting, upon the opposite face of which casting may be mounted a plate not shown. This plate is placed against the finished end 5 and attached to the casting by bolts through the holes 6, such plate being removable for inspection purposes. This projecting portion of the casting 3 while flat on either end is generally circular save for a flattened top 7 through which access may be had to the valves and ignition apparatus hereinafter described. This arrangement permits of the ready access by the operator to the top of the valves, valve seats and ignition apparatus.

On the interior of the casting there will be noted an intake valve housing 8 and a similar shaped exhaust valve housing 9.

Referring to Figure 1, Figure 6 and Figure 9, it will be seen that the intake fuel is admitted into the casting through the aperture 10 which fits with the corresponding aperture in the cylinder construction to which this casting is bolted. The intake gases pass through the passageway 11 between the outside wall 3 of the casing and the inner wall 12 on the inside of the casing. This passageway enlarges as at 13 where it merges into an area designated 14 beneath the intake valve 15. The fuel passes outwardly beneath the valve 15 into the interior of the valve casing 8 in an area generally designated 16 and thence into the cylinder through the intake port 17. Mounted on the top of the intake casing 8 is the ignition apparatus consisting of an arc shaped support 18 which carries the spark plug 19 in a cup 20. The current is conveyed to the plug by the cable 21 carried in the conduit 22 which is mounted with a gas tight fit in the sleeve 23 of the connection 24 which is mounted with a gas tight fit at 25 on the cup 20. The control plate 26 is mounted on the lower end of a shaft 27 beneath the cup 20 and is adapted to contact with the spark plugs 19 as desired. The shaft 27 also carries insulating members 28, between which is mounted a contact 29 for the end of the plug 19. This shaft 27 is controlled by a handle 30 mounted on the upper end of the shaft within the connection 24, above the platform 7 of the casting so as to give ready access to it for the control of the ignition by the operator. This cup itself is sealed by the packing 31 on top of the plat-

form 7 of the casting while the lower portion of the cup is sealed with a packing 32 within the top of the valve casing 8. It is apparent that this whole unit constituting the top of the valve casing, the enclosure 70 for the main casing and the gas tight container for the ignition apparatus may be lifted, when desired, bodily from the casting giving access to the valve 15. This valve 15 rests upon a detachable ring 33 in the base of the casing 8. The valve itself is threaded as at 34 on its valve stem 35. This valve stem 35 is carried in a lengthened sleeve or guide 36 which is provided with a shoulder 37 for contact with the casing which at this point is formed into an enlarged tubular or cylindrical member 38. This member 38 is provided with an orifice at its upper end in which fits the reduced portion of the sleeve 36. The shoulder 37 on the sleeve 36 abuts against the inner surface of the top portion of the sleeve 38. This sleeve is tapered on its exterior as at 40 so that a valve spring 41 may rest against the outside of the shoulder 37 surrounding the sleeve and the valve stem. The lower end of this spring rests upon a tappet block 42 inserted in the base 42^a provided with a suitable opening 42^b shown in Figure 18. 85 This block is formed with a shoulder 43 engaging with the corresponding shoulder on the bottom of the stem 35. It is threaded as at 44 on the lower end of the stem. The lower end of the block is cut as at 45 to receive the tappet 46 which is also threaded on the lower end of the valve stem as at 47. 90 This tappet is adjusted in its position in respect to the block by the set screws 48. 95 100

Surrounding the valve casing 8 are the water passageways 49 which connect through the openings 50 with the cooling chambers of the cylinder. The water circulates around the valve casings in the space 51 between the casings and on the other side of the exhaust valve 9 in the passageway 52. Thus the valve casings are completely cooled. A large cooling area as at 53 is provided below the valve casings and generally between them. A similar passageway below the exhaust passageway is provided at 54. 115

The water so circulates that it not only cools the valve casings, but also cools the back of the cylinder head 55 which has a convex structure forming the inner wall of the valve casting and integral therewith, being pierced by the intake opening 17 and an exhaust opening 56. The arc shaped connection between the casings of the two valves, such casing being formed of a continuous wall, is designated 57. These casings being integral with the cylinder head 55 serve to support it and assist in compensating for the expansion and contraction of the several parts. This construction is more clearly seen in Figure 9 and in Figures 8 120 and 125

and 10. Within the wall 3 of the casting are the valve casings and the guides for the valve stems spaced from the wall 3 except at the points where the valve casings and wall 3 are united for supporting purposes. Each of these valve casings are connected together and act as a support for the convex cylinder head of which they are a part and through which they communicate with the interior of the cylinder. The entire structure comprising an integral wall by reason of the single casting has great strength. Further, as the parts are heated from the same source and cooled by the same medium they inevitably expand and contract under the same conditions, whereby the structure as a whole is maintained in the same relative condition thus preventing any warping or breakage due to uneven temperatures. This is due to the water circulating between the closely adjacent inner and outer walls of the casting which maintains the entire structure at a uniform temperature.

The valve casing 9, as will be seen particularly in Figure 10, is mounted upon a second casing integral therewith which forms the exhaust chamber, such casing being designated 58. It is in turn mounted upon the vertical tubular casing 59 which is integral with and supported by the outside casting. It is so formed that it has a cylindrical member fitting at its lower end in the opening 59^a in the bottom 42^a and opening at its upper end into the discharge chamber 60 below the seat 61 for the valve ring 62 upon which rests the exhaust valve hereinafter described. This exhaust chamber 60 increases to the size of the exhaust manifold 65, as shown at 64. This manifold is bolted to the casting and is provided with water circulating passageways 66 and an inner wall 67. The exhaust passage in the manifold is designated 68. The water circulation passageways 66 communicate with water circulation passageways in the casting.

The valve itself used for exhaust purposes is constructed as follows. It has a seat portion designated 63 and cup portion 69 for mounting the seat upon a valve stem 70 which is hollow. This stem is provided with a shoulder 71 upon which rests the cup 69 having a similar cut out shoulder so that the cup is supported on the stem. The upper end of the stem is threaded at 72 for receiving a nut 73 for engaging the upper end of the valve cup within the valve seat, thus providing this connection within the valve in a water cooled area and clamping the cup between the shoulder 71 and the nut 73 on the stem 70. The valve seat mounted upon the valve cup is continued inwardly and upwardly by the cylindrical wall 74 which is drawn inwardly into a throat to give the greatest area possible

within the valve casing for the exit of the gases while at the same time providing an area 75 within the valve for the circulation of a carrying fluid. The upper ends of the wall 74 terminate in a piston head having a long skirt 76 provided with a number of packing rings 77. This piston head works within a cylindrical member 78 mounted in the upper end of the valve casing 9 and sealed thereto by the packing ring 79. The inner end of this piston head which has a threaded aperture 80 is filled with a screw plug 81 upon a shoulder 82 upon which is mounted the valve spring 83. The interior of this plug is provided with an aperture 84. A tubular member having a shoulder 85 and being designated 86 is mounted within this aperture. This tubular member provides a passageway 87 for carrying fluid to make its exit as will be hereinafter described. The upper end of this tubular member 86 is threaded as at 88 and carries a head 89 sliding in the cap member 90 which forms the upper abutment for the spring 83 of the valve. This cap 89 is provided with an exit passageway 90^a for the carrying fluid. The passageway 90^a connects with the exit area 91 which in turn connects with the passageway 87 through which the carrying fluid rises for its exit. This cap member is divided into two compartments 91 and 92 separated from one another by the wall 93. This wall carries a delivery tube 94 for the carrying fluid. The area 92 is connected to a pipe 95 which is the supply pipe for the carrying fluid and which in turn is connected to a flexible pipe 96. This is necessary because the entire structure just described is mounted upon, and moves with, the valve, save for the abutment 90 for the valve spring in which this mechanism slides. This tube 94 is carried down from the passageway 87, passageway 75, through the interior of the valve stem 70 to nearly the bottom of the tubular interior of the valve stem 70 at which point it delivers its carrying fluid which rises within the valve stem 70 into the passageway 75 through the passageway 87 into 91 and thence out the exit 90^a. The lower end of the valve stem is threaded to carry a tappet block or roller as at 97 mounted in the bottom 42^a of the casting in the opening 59^a. The interior of this casting is provided with a series of ribs radiating from the center of the cylinder head outwardly and rearwardly through the exterior wall of the casting. These ribs are marked 98, 99, 100, 101, 102, 103, 104, 105, 106, 107 and 108. These ribs merge into the convex head 55 as seen more particularly in Fig. 7. It is noted that the ribs terminate at the enlarged eyes for the reception of the attaching bolts and are concentrated at their inner ends at 130

4
their center 110 which is the center of the convex cylinder head. Such ribs will be seen illustrated in Figures 1, 6 and 7 as well as in other figures. Thus the entire structure is tied together and braced.

It will be understood that I desire to comprehend within my invention such modifications as may be found necessary to adapt it to varying conditions of use. I do not desire to confine myself to the specific configurations or detail arrangements.

Having thus fully described my invention, what I claim as new and desire to secure by Letters Patent, is:—

15 1. In an internal combustion engine, a cylinder head construction consisting of a casting, one wall of which is formed by a convex cylinder head, water passageways connecting with the cylinder for circulating water within the casting behind the head, a plurality of ribs adapted to support said cylinder head, said ribs being disposed with their outer bottoms on the casting and their inner ends merging towards the center of the cylinder head, and integral valve casings located within said casting and providing a support for said cylinder head.

2. In an internal combustion engine, a cylinder head construction consisting of a casting, one wall of which is formed by a convex cylinder head, water passageways connecting with the cylinder for circulating water within the casting behind the head, a plurality of ribs adapted to support said cylinder head, said ribs being disposed with their outer bottoms on the casting and their inner ends merging towards the center of the cylinder head, integral valve casings located within said casting and providing a support for said cylinder head, and having openings from the valve casings through the cylinder head to form entrance and exit ports.

3. In an internal combustion engine a cylinder head construction consisting of a casting, one wall of which is formed by a convex cylinder head, water passageways connecting with the cylinder for circulating water within the casting behind the head, a plurality of ribs adapted to support said cylinder head, said ribs being disposed with their outer bottoms on the casting and their inner ends merging towards the center of the cylinder head, integral valve casings located within said casting and providing a support for said cylinder head, having openings from the valve casings through the cylinder head to form entrance and exit ports, and integral tubular portions formed in said casting to serve as guides for valve stems of valves working in said valve casings.

4. In an internal combustion engine, a cylinder head construction consisting of a casting, one wall of which is formed by a convex cylinder head, water passageways

connecting with the cylinder for circulating water within the casting behind the head, a plurality of ribs adapted to support said cylinder head, said ribs being disposed with their outer bottoms on the casting and their inner ends merging towards the center of the cylinder head, integral valve casings located within said casting and providing a support for said cylinder head, having openings from the valve casings through the cylinder head to form entrance and exit ports, one of said valve casings being adapted to support ignition apparatus and the other of said casings valve cooling apparatus.

5. In an internal combustion engine, a cylinder head construction consisting of a casting, one wall of which is formed by a convex cylinder head, water passageways connecting with the cylinder for circulating water within the casting behind the head, a plurality of ribs adapted to support said cylinder head, said ribs being disposed with their outer bottoms on the casting and their inner ends merging towards the center of the cylinder head, integral valve casings located within said casting and providing a support for said cylinder head, having openings from the valve casings through the cylinder head to form entrance and exit ports, one of said valve casings being adapted to support ignition apparatus and the other of said casings valve cooling apparatus, said main casting having one end detachable for the inspection of the interior of the casting and the exterior of the valve casings.

6. In an internal combustion engine, a combined cylinder head, valve casings, a cooling casing consisting of a drumlike exterior casting, a substantially vertical convex wall on one side to form a cylinder head, means of attaching the drumlike casting to the cylinder casing, valve casings inside the drumlike casting and spaced therefrom to form water passageways, said valve casings being cast with the cylinder head and having connecting ports therethrough, said casting having water inlet ports and exhaust ports connecting with the cylinder walls and exit manifold and having circulating passageways for the water around the valve casings, the cylinder head and passageways formed with said casting communicating with the valve casings to constitute inlet and exit passageways.

7. In an internal combustion engine, a combined cylinder head, valve casings, a cooling casing consisting of a drumlike exterior casting, a substantially vertical convex wall on one side to form a cylinder head, means of attaching the drumlike casting to the cylinder casing, valve casings inside the drumlike casting and spaced therefrom to form water passageways, said valve casings being formed with the cylinder head

and having connecting ports therethrough, said casting having water inlet ports and exhaust ports connecting with the cylinder walls and manifold and having circulating 5 passageways for the water around the valve casings, the cylinder head and passageways formed with said casting communicating with the valve casings to constitute inlet and exit passageways, and integrally formed 10 tubular casings supporting the valve casings to form guides for the valve stems of the valves in the valve casings, said tubular members being formed in the drumlike casting.

15 8. In an internal combustion engine, a combined cylinder head, valve casings, a cooling casing consisting of a drumlike exterior casting, a substantially vertical convex wall on one side to form a cylinder head, 20 means of attaching the drumlike casting to the cylinder casing, valve casings inside the drumlike casting and spaced therefrom to form water passageways, said valve casings being formed with the cylinder head and 25 having connecting ports therethrough, said main casing having water inlet ports and exhaust ports connecting with the cylinder walls and exit manifold and having circulating passageways for the water around 30 the valve casings, the cylinder head and passageways formed with said casting communicating with the valve casings to constitute inlet and exit passageways, and integrally formed tubular casings supporting the valve 35 casings to form guides for the valve stems of the valves in the valve casings, such tubular members being formed in the drumlike casting, said drumlike casing having a detachable head opposite to the side on 40 which is located the cylinder head.

45 9. In an internal combustion engine, a combined cylinder head and valve casing construction consisting of an outside casing, a cylinder head mounted on one side there- 50 of and supported thereon by a plurality of ribs, said cylinder head being spaced from the main casing to permit of the entrance of a cooling fluid from the cylinder walls behind the cylinder head and around the 55 valve casings in said main casing, valve casings therein attached to and forming a part of the cylinder head and having ports through said cylinder head and ports through said main casing.

60 10. In an internal combustion engine, a combined cylinder head and valve casing construction consisting of an outside casing, a cylinder head mounted on one side there- 65 of and supported thereon by a plurality of ribs, said cylinder head being spaced from the main casing to permit of the entrance of a cooling fluid from the cylinder walls behind the cylinder head and around the valve casings in said main casing, valve cas- 70 ings therein attached to and forming a part

of the cylinder head and having ports through said cylinder head and ports through said main casing, said valve casings and passageways for constituting intake and outlet ports being formed integrally with the main casing and supported thereon by tubular casings to form slides for the valve stems.

11. In an internal combustion engine, a combined cylinder head and valve casing construction consisting of an outside casing, a cylinder head mounted on one side thereof and supported thereon by a plurality of ribs, said cylinder head being spaced from the main casing to permit of the entrance of a cooling fluid from the cylinder walls behind the cylinder head and around the valve casings in said main casing, valve casings therein attached to and forming a part of the cylinder head and having ports through said cylinder head and ports through said main casing, said valve casings and passageways for constituting intake and outlet ports being formed integrally with the main casing and supported thereon by tubular casings to form slides for the valve stems, the upper ends of said casings being open beneath openings in said main casing to permit of the location and adjustment or removal of the valves and ignition mechanism. 80

12. In an internal combustion engine, a combined cylinder head and valve casing construction consisting of an outside casing, a cylinder head mounted on one side thereof and supported thereon by a plurality of ribs, said cylinder head being spaced from the main casing to permit of the entrance of a cooling fluid from the cylinder walls behind the cylinder head and around the valve casings in said main casing, valve casings therein attached to and forming a part of the cylinder head and having ports through said cylinder head and ports through said main casing, said valve casings and passageways for constituting intake and outlet ports being formed integrally with the main casing and supported thereon by tubular casings to form slides for the valve stems, the upper ends of said casings being open beneath openings in said main casing to permit of the location and adjustment or removal of the valves and ignition mechanism, said tubular valve stem casings being located beneath the apertures aforementioned so that there is a passage- 100 way through said casing through the valve chambers. 110

13. In a cylinder head, a valve cooling construction, a casing, a pair of vertically arranged valve casings therein spaced therefrom and from each other to provide water circulating passageways, an intake passage- 125 way communicating with one valve casing, an exit passageway communicating with the other valve casing, a cylinder head carried 130

by said valve casings, said head having ports communicating with said valve casings, vertically arranged tubular casings supporting the valve casings for use as guides for valve stems, said intake and exit passageways being laterally disposed at the lower ends of said valve casings, and valve cooling mechanism mounted in the open top of one of said valve casings and ignition mechanism mounted in the top of the other of said valve casings.

14. In a cylinder head, a main shell, a pair of tubular valve casings joined together by a U-shaped wall and a convex cylinder head supported by said wall and portions of the casings, whereby the structure will be integral but independent expansion will be permitted relatively of the valve casings depending upon their temperature.

In testimony whereof, I affix my signature.

ELMER A. WATTS.
